(57) **CLAIM**

The ornamental design for a voice recognition speaker, as shown and described.

DESCRIPTION

FIG. 1 is a perspective view of a voice recognition speaker showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is an enlarged view of a representative portion of FIG. 4.

The broken lines shown in the drawings are included for purposes of illustrating portions of the voice recognition speaker and form no part of the claimed design. In FIGS. 1-2 and 4, the upper surface of the top of the voice recognition speaker has a surface with the pattern depicted in FIG. 8.
